SAFETY RAZOR BLADE

Filed Aug. 19, 1933

Fig. 4.

Inventor—

Edward R. Wharton,
By Arthur T. Randall
Atty.

UNITED STATES PATENT OFFICE

2,011,025

SAFETY RAZOR BLADE

Edward R. Wharton, Medford, Mass.

Application August 19, 1933, Serial No. 685,939

1 Claim. (Cl. 30—12)

My invention relates to flexible safety razor blades of that class which are provided with cutting edges upon opposite sides thereof and it has for its object to provide an improved blade of this kind. It is also an object of this invention to provide an improved safety razor blade especially adapted and designed for use in connection with the blade-holder shown and described in my co-pending application for patent, Serial No. 685,938 filed on or about the 19th day of August, 1933, now Patent No. 1,984,243 granted December 11, 1934.

To these ends I have provided a double-edged safety razor blade of thin, flexible sheet steel having oppositely disposed side cutting edges, said blade being formed with two straight longitudinal rows of spaced apart apertures, one of said rows being parallel with and adjacent to one of said cutting edges and the other row being similarly disposed with relation to the opposite cutting edge so as to provide an un-apertured, relatively wide, median zone between said rows and two relatively narrow un-apertured side marginal zones outside of said rows which are parallel with said median zone and connected with the latter by the material of the blade that is between the apertures of the rows and at the opposite ends thereof.

In the accompanying drawing:

30 Figure 1 is a plan view of a safety razor blade made in accordance with my invention.

Figure 2 is a section on line 2—2 of Fig. 1.

Figure 3 is an end view of the blade shown in Fig. 1.

35 Figure 4 illustrates another form of the invention.

The two illustrated embodiments of my invention are safety razor blades which are constructed and adapted to be used in the holder illustrated and described in my above noted co-pending application, the only difference between the two forms shown being in the shapes of the apertures.

The blade illustrated in Fig. 1 is a thin, flexible length of hardened and tempered sheet steel having its opposite sides beveled to provide relatively parallel cutting edges 10 and having its intermediate portion formed with two rows of spaced apart apertures 11, one of said rows being adjacent to and parallel with one of said cutting edges and the other similarly disposed with respect to the opposite cutting edge.

Each row of apertures 11 is disposed about midway between the longitudinal median line of the blade, as viewed in Fig. 1, and the adjacent cutting edge 10 so that the blade is divided into

three longitudinal un-apertured zones including a longitudinal median zone 12 and two longitudinal side marginal zones 13.

The apertures 11 are provided to receive the hooks of the blade flexing levers of the holder of said co-pending application and when said levers are operated to flex the blade the outermost sides of the apertures co-operate with the hooks of said levers to properly position the blade with respect to the guard of said holder immediately before the blade is flexed. When the holder is operated to flex my new blade the median zone 12 and the side marginal zones 13 provide abutment surfaces for said flexing levers and it is for this reason that said zones should be imperforate or at least constructed so as to cooperate with said levers. It is also a feature of this invention that each row of holes or apertures 11 consist of several such holes or apertures for engagement with the levers of the flexing mechanism of the razor referred to and in order that the blade when flexed transversely by the levers will be flexed uniformly throughout its extent the zone connecting necks 14 are made substantially greater in width than the width of the apertures 11. In other words, the size of each aperture 11 is so small as compared with the size of each neck 14 that the presence of said apertures does not materially weaken the blade in the region of said holes or apertures.

When the blade is flexed by the levers only the median zone 12 and the material of the blade that is between the apertures is bent or distorted transversely, the opposite side marginal zones 13 merely swinging bodily, without distortion, toward or from the guard as the levers referred to are operated in one direction or the other. This absence of distortion within the side marginal zones 13 is mainly due to the reinforcing effects of the necks 14 of blade material which alternate with the apertures 11, said necks being a characterizing feature of the invention common to both forms of blades herein illustrated.

A razor blade constructed as above described has its advantages over safety razor blades of this class as heretofore constructed wherein one or more locating apertures were provided at the middle thereof with the result that the blade was weakened to such an extent along its median line that it was frequently broken. Also, this weakness at the median line of some of the blades heretofore proposed resulted in distortion of the cutting edge when the blade was flexed by its holder.

My new blade is devoid of locating apertures 55

along the line of greatest flexure and those apertures which are provided are disposed along lines of least flexure and as a result it is strong and durable.

5. What I claim is:

A safety razor blade of thin flexible resilient sheet metal having oppositely disposed parallel side cutting edges and formed with two straight parallel longitudinal rows of several relatively 10 small spaced apart apertures for the reception of the blade-flexing mechanism of a blade holder of the character described, one of said rows being parallel with and adjacent to one of said cutting

edges and the other row being similarly disposed with relation to the opposite cutting edge so as to provide an imperforate, relatively wide, median abutment zone between said rows and two relatively narrow imperforate side marginal 5 abutment zones outside of said rows which are parallel with said median zone and each of which is connected with the latter by a plurality of relatively large neck portions which alternate with the relatively small apertures adjacent thereto 10 so that the blade is of approximately uniform flexibility transversely throughout its extent.

EDWARD R. WHARTON.
